VACUUM TUBE VOLTMETER

William W. Hartz, Springfield, N. J., assignor to Weston Electrical Instrument Corporation, Newark, N. J., a corporation of New Jersey

Application June 7, 1954, Serial No. 30,844

Term of patent 14 years

(Cl. D26—5)

The single figure is a perspective view of a vacuum tube voltmeter, showing my new design. The opposite side, not shown, is substantially the same as the side shown, and the back thereof is conventional. Portions of the figure are diagonally lined to indicate transparency.

I claim:

The ornamental design for a vacuum tube voltmeter, substantially as shown and described.
